US00D597202S

(12) **United States Design Patent**
Reid et al.

(10) **Patent No.:** US D597,202 S
(45) **Date of Patent:** ** Jul. 28, 2009

(54) **RESPIRATORY MASK**

(75) Inventors: **Michael John Reid**, Stanmore (AU); **Dimitri Marco Maurer**, Umina (AU); **Amal Shirley Amarasinghe**, West Pennant Hills (AU); **Aaron Samuel Davidson**, Newport (AU); **Angelene Marie Ozolins**, Wahroonga (AU); **Lemmy Nga**, Glenwood (AU); **Scott Alexander Howard**, Harbord (AU); **Alison Oldenburg**, Crows Nest (AU); **Bart Jeremy Caffin**, North Manly (AU)

(73) Assignee: **Resmed Limited**, Bella Vista, New South Wales (AU)

(**) Term: **14 Years**

(21) Appl. No.: **29/309,587**

(22) Filed: **Sep. 8, 2008**

(51) LOC (9) Cl. **29-02**

(52) U.S. Cl. **D24/110.1**

(58) Field of Classification Search D24/110.1, D24/110.4, 110.5, 164; 128/205.25, 206.27, 128/207.11, 206.26, 207.17, 207.13, 206.21, 128/204.18, 206.12

See application file for complete search history.
